UNITED STATES PATENT OFFICE.

EDWARD D. LELAND, OF PITTSBURGH, PENNSYLVANIA, ASSIGNOR OF ONE-HALF TO
FRITZ UHLENHAUT, JR., OF PITTSBURGH, PENNSYLVANIA.

GAS-BURNER.

1,322,249.

Specification of Letters Patent. Patented Nov. 18, 1919.

Application filed April 18, 1918. Serial No. 229,276.

To all whom it may concern:

Be it known that I, EDWARD D. LELAND, a citizen of the United States, and resident of Pittsburgh, in the county of Allegheny and State of Pennsylvania, have invented a new and useful Improvement in Gas-Burners; and I do hereby declare the following to be a full, clear, and exact description thereof.

10 My invention relates to an improvement in gas burners for use under boilers, heating furnaces, etc.

The object of my invention is to provide a burner which makes it feasible to burn gas efficiently under various conditions of draft, and also where the gas is delivered to the burner under either a high pressure—as, for example, forty pounds per square inch—or under a very low pressure—as, for 20 example, one inch of water pressure. The difficulty with most gas burners now in use is that when the gas pressure is low and the draft is poor, there is danger of the gas igniting near the mixer and injuring the 25 burner. If, in order to prevent this trouble, excess or secondary air is used to protect the burner, loss of efficiency is the result. By my invention no excess air is needed to protect the burner, as there is no danger of 30 the igniting gas injuring the burner.

To these ends my invention comprises the novel features hereinafter set forth and claimed.

In the accompanying drawing, Figure 1 35 is a sectional view of a portion of a boiler furnace showing my improved burner applied thereto; Fig. 2 is an enlarged face view of a portion of the furnace front showing the shutter removed; Fig. 3 is an enlarged sectional view of the front end of the 40 furnace showing my improved burner in position; Fig. 4 is a section on the line 4—4, Fig. 3; and Fig. 5 is a detail of the shutter-plates.

45 In the drawing, the numeral 2 indicates a common form of boiler furnace with the boiler 3 resting thereon. The front wall 4 of the furnace has an opening 5 formed therein to receive the fire-brick or other refractory mixing plate or tile 6 formed with the perforations or passages 7. The number of said passages will depend upon the size and capacity of the furnace, as well as the sizes of said passages. The passages or perforations 7 may be of any suitable

shape, but especially in the case of very low gas pressures they are preferably provided with curved or spiral vanes or blades 8, said vanes or blades being likewise formed of some refractory material. The purpose of 60 these plates or vanes is to give the inflowing air a swirling motion, which hastens its mixing with the gas delivered to said passages.

Located in front of the furnace is the 65 box or casing 9, which is formed of cast or wrought iron, connected up to the supply-pipe 10, a valve 11 being provided to control the supply of gas to the burner.

Projecting from the box 9 are the pipes 70 12, which pipes deliver gas to the passages 7.

In order to regulate or control the supply of air to the burner, I provide shutter-plates 13 and 14. The shutter-plate 13 has the openings 15 which register with the passages 75 7 and through which the pipes 12 extend into said passages. The outer shutter-plate 14 is movable and is provided with the openings 16, which register with the openings 15 of the movable plate 13. 80

The bolts 17 extending into the furnace-wall serve to hold the shutter-plates in position and slots 17^a are provided to allow for the movement of said plates.

The outer movable shutter-plate 14 has 85 the slot 18 through which the stud 19 on the inner plate projects. The outer plate has the stud 19^a. A lever 19^b is pivoted on the bolt 17^a and said lever is connected to the pins 19, 19^a. It will be apparent that when 90 the lever is moved the plates will move in opposite directions to enlarge or decrease the shutter openings.

The openings 15 and 16 of the shutter-plates are preferably shaped as illustrated so 95 that when one plate is moved over the other, the air inlet may be cut down to the shape indicated in Fig. 5. By the use of these shutter-plates, the amount of air admitted is readily controlled, but even without said 100 shutter, highly efficient results are obtained with my improved burner. Any other suitable method of controlling the admission of air may be employed.

When my improved burner is in use, the 105 gas admitted by the pipes 12 enters the passages 7, and the air entering the openings is given a whirling motion, which tends to expedite its mixture with the gas in the mixing plate so that when the gas reaches 110

the point of ignition within the furnace, better combustion is obtained, and the supply of air may be so regulated as to give efficient results under various conditions of draft, as 5 well as in cases where the gas is delivered either under a high or low pressure.

What I claim is:

1. In a gas burner, the combination with a furnace wall, of a refractory mixing-plate 10 set therein having a plurality of mixing passages extending through it with open outer ends communicating directly with the atmosphere whereby all the air for mixing and combustion enters said open ended passages, a box, means for supplying gas to 15 said box, and individual pipes leading from said box to said mixing passages whereby the combustion takes place at the discharge ends of said passages.
2. In a gas burner, the combination with a furnace wall, of a refractory mixing-plate set therein having mixing passages extending through it with open outer ends communicating directly with the atmosphere where- 20 by all the air for mixing and combustion 25

enters said open ended passages, individual gas pipes extending into said passages, and a shutter arranged so as to control simultaneously the supply of air directed from the atmosphere to each individual mixing 30 passage whereby the combustion takes place at the discharge ends of said passage.

3. In a gas burner, the combination with a furnace wall, of a refractory mixing-plate set therein having a plurality of mixing pas- 35 sages extending through it with open outer ends communicating directly with the atmosphere, individual gas pipes extending into said passages, movable shutter-plates having openings through which said pipes 40 extend, and means for moving said plates in opposite directions for controlling the supply of air to said mixing passages.

In testimony whereof, I, the said EDWARD D. LELAND, have hereunto set my hand.

EDWARD D. LELAND.
